(57) **CLAIM**

I claim the ornamental design for a depilatory device, as shown and described.

DESCRIPTION

FIG. 1 is a front perspective view of a design of the depilatory device;

FIG. 2 is a front elevation view of the design of the depilatory device of FIG. 1;

FIG. 3 is a rear elevation view of the design of the depilatory device of FIG. 1;

FIG. 4 is a first side elevation view of the depilatory device of FIG. 1;

FIG. 5 is a second side elevation view opposite the first side elevation view of FIG. 4;

FIG. 6 is a top plan view of the depilatory device of FIG. 1;

FIG. 7 is a bottom plan view opposite the top plan view of FIG. 6; and,

FIG. 8 is a rear perspective view of the depilatory device of FIG. 1.

The features shown in broken lines depict environmental subject matter only and form no part of claim design.
